UNITED STATES PATENT OFFICE.

JOHN BACON FOX, OF CHICAGO, ILLINOIS.

DESIGN FOR A BURGLAR-ALARM.

SPECIFICATION forming part of Design No. 35,267, dated November 5, 1901.

Application filed August 24, 1901. Serial No. 73,207. Term of patent 7 years.

To all whom it may concern:

Be it known that I, JOHN BACON FOX, a citizen of the United States, and a resident of Chicago, in the county of Cook and State of Illinois, have invented and produced a new and original Design for Burglar-Alarms, of which the following is a specification, reference being had to the accompanying drawings, forming a part thereof.

10 In the accompanying drawings, Figure 1 is a side elevation of a burglar-alarm made according to my new design. Fig. 2 is a bottom plan of same.

15 The leading feature of my design is the burglar-alarm, consisting of the spheroidal body having the pointed projection 1 extending from the periphery of said body and tapering toward its free end, and the plate 5, lying against the under side of said body, hav-

ing the recess 6 in its rear end forming the 20 projections 2, which are disposed downwardly under the rear part of said body and having its forward end disposed downwardly at substantially right angles under the forward part of said body, said features being formed and 25 arranged to produce a configuration substantially as shown.

What I claim as new, and desire to secure by Letters Patent, is—

The design for a burglar-alarm, substantially as herein shown and described.

Signed by me at Chicago this 22d day of August, 1901.

JOHN BACON FOX.
